CLAIM

The ornamental design for a pantry shelf, as shown and described.

DESCRIPTION

FIG. 1 is a front elevational view of a pantry shelf showing my new design;

FIG. 2 is a front elevational view thereof;

FIG. 3 is a top plan view thereof; and,

FIG. 4 is an end elevational view, the opposite end being identical.

The rear and bottom of the pantry shelf are conventionally plain and unadorned.

FIG. 2.

FIG. 3.

FIG. 4.
